UNITED STATES PATENT OFFICE.

CHARLES TWINING, OF LOCUST POINT, NEW JERSEY.

SMOKER'S POUCH.

1,096,771.

Specification of Letters Patent.

Patented May 12, 1914.

Application filed September 24, 1912. Serial No. 722,042.

To all whom it may concern:

Be it known that I, CHARLES TWINING, a subject of the King of Great Britain, and a resident of Locust Point, Monmouth county, 5 State of New Jersey, have invented certain new and useful Improvements in Smokers' Pouches, of which the following is a full, clear, and exact description.

This invention relates to pouches for use 10 by smokers, and has reference more particularly to a device of this kind which serves both as a container for tobacco and a holder for a smoker's utensil such as a pipe.

The invention further relates to a smoker's pouch fashioned from flexible or pliable material and comprising a compartment for tobacco and a compartment for a pipe or like utensil.

My invention, in addition, contemplates 20 the provision of a smoker's pouch which consists of an outer envelop, and an inner envelop adapted to be disposed within the outer envelop, the latter having means also for holding a pipe or like device, the inner 25 envelop constituting a container for tobacco or similar substance.

An object of the invention is to provide a simple, inexpensive and durable pouch for smokers, which can be fashioned from different material adapted for the purpose, and in different forms, sizes and styles, which constitutes a compact and efficient container both for tobacco and a utensil for using the tobacco, such as a pipe, which is flexible or 35 pliable, so that it will readily accommodate itself to the bulk of its contents and will conform to the pocket of the user, which can be readily and easily manipulated, in which the tobacco and the pipe are always 40 available for immediate use, and in which the contents are securely held against accidental escape.

A further object of the invention is to provide a device of the class in question, 45 which can be used for tobacco and a pipe, or as a holder for tobacco alone, in which the tobacco-containing compartment is similar to a tobacco pouch commonly in use which has been found to be of convenient and 50 practicable design, and in which the outer envelop constitutes both a holder for a pipe and a protection or cover for the inner, or tobacco-containing compartment.

The invention consists in the construction 55 and combination of parts to be more fully

described hereinafter and particularly set forth in the claims.

Reference is to be had to the accompanying drawings forming a part of this specification, in which similar characters of reference indicate corresponding parts in all the views, and in which—

Figure 1 is a plan view of an embodiment of my invention, a part being broken away to show details of construction; Fig. 2 is a 60 transverse section of the device, showing the same closed; and Fig. 3 is an end elevation of the pouch, certain of the parts being indicated in different positions in dotted outlines, and a portion being broken away and 65 in section.

Before proceeding to a more detailed explanation of my invention it should be understood that the same is fashioned either wholly or partly from flexible or pliable material such as soft rubber, leather, fabric or the like. I prefer to employ soft rubber and 70 leather.

Referring more particularly to the drawings I have shown for example, an embodiment of the pouch comprising a tobacco receptacle or compartment 5 consisting of two parts 6 and 10, joined integrally and of soft rubber, leather or like flexible material. The parts 6 and 10 are similar and symmetrical, being of rounded form and substantially semi-circular. The compartment 5 has an opening 8—9 intermediate the parts 6 and 10, and extending from one edge to the other. The edges 8—9 of the opening form 80 respectively, the edges of the parts 6 and 10. I prefer to bead or rib the edge 8 to strengthen the construction. The compartment 5 is in effect a tobacco pouch of a form 85 commonly in use today, the part 10 being adapted to be folded within the part 6 when the pouch is closed. In this position of the elements 6 and 10 the opening 8—9 is of 90 course closed. In Fig. 1 the pouch is shown with the compartment 5 open for the introduction or removal of tobacco A. In Figs. 2 and 3 it is shown closed with the opening 8—9 covered by a portion of the material of the part 10.

The pouch has an outer envelop or compartment 7 fashioned preferably from flexible material. It is substantially rectangular in form, with rounded edges and corners, and is integrally or otherwise attached 105 along two edges to the compartment 5. The 110

attachment of the two compartments is adjacent to the edge 8, and at the back of the compartment 5. The part 6 of the tobacco compartment is normally disposed within 5 the outer envelop 7 as is clearly shown in Fig. 1. The outer envelop is so proportioned that there is room therein not only for the part 6 of the compartment, but, in addition, for a pipe 12 or other smoker's 10 utensil. The outer envelop has preferably at one of its ends an opening 14 extending from side to side thereof and provided with thickened edges 15 in which are embedded leaf springs or strips 13 which serve normally to hold the opening closed. By pressing at the corners of the opening the springs 15 will be bowed as indicated in dotted outline in Fig. 3, so that the end of the outer envelop is opened for the withdrawal or 20 insertion of the pipe 12.

While I prefer to fashion the tobacco-receiving compartment in the form shown herewith, it will be remembered that it may be given any other shape or may be of any 25 other type adapted for the purpose. The substantially semi-circular shape can also be departed from in order to increase its capacity. By providing two openings the cleanliness of the outer compartment is also enhanced, whereby it is rendered sanitary and 30 odorless.

Having thus described my invention, I claim as new, and desire to secure by Letters Patent:—

35 1. A smoker's pouch comprising an outer inclosing compartment and a tobacco compartment formed of flexible material and having a flexible folding connection between said compartments, the tobacco compartment having a rounded outer edge and being relatively smaller than the outer inclosing compartment, the said outer inclosing compartment being substantially rectangular and provided with a pipe receiving chamber

below the rounded edge of the tobacco compartment when said tobacco compartment is folded within the outer inclosing compartment. 45

2. A smoker's pouch comprising an outer inclosing compartment and a tobacco compartment formed of flexible material, a flexible folding connection between said compartments, the tobacco compartment being relatively smaller than the outer inclosing compartment, said outer inclosing compartment provided with a pipe receiving chamber, and an opening leading to said chamber independent of the opening to receive the tobacco compartment. 50 55

3. A smoker's pouch comprising an outer inclosing compartment and a tobacco compartment formed of flexible material, a flexible folding connection between said compartments, the tobacco compartment being relatively smaller than the outer inclosing compartment, said outer inclosing compartment provided with a pipe receiving chamber, and an opening in the outer compartment at one end thereof leading to said pipe receiving chamber. 60 65 70

4. A smoker's pouch comprising an outer inclosing compartment and a tobacco compartment formed of flexible material, a flexible folding connection between said compartments, the tobacco compartment being relatively smaller than the outer compartment, said outer compartment having a pipe receiving chamber, an opening in the outer compartment at one end thereof leading to said pipe receiving chamber and a spring 75 80 clasp for said opening.

In witness whereof I have signed my name to this specification in the presence of two subscribing witnesses.

CHARLES TWINING.
